SLEEPING GARMENT FOR INFANTS

Stella M. Godfrey, Sun Valley, Calif.

Application August 5, 1949, Serial No. 4,310

Term of patent 7 years

(Cl. D92—2)

To all whom it may concern:

Be it known that I, Stella M. Godfrey, a citizen of the United States and a resident of the city of Sun Valley, in the county of Los Angeles and State of California, have invented a new, original, and ornamental Design for a Sleeping Garment for Infants, of which the following is a specification, reference being had to the accompanying drawings, forming part thereof, in which:

Fig. 1 is a front view; and

Fig. 2 is a rear view of an infant's sleeping garment embodying my new design.

I claim:

The ornamental design for a sleeping garment for infants, as shown.

STELLA M. GODFREY.
